[57] **CLAIM**

The ornamental design for a water jet for producing whirlpool action in bathtubs, as shown and described.

DESCRIPTION

FIG. 1 is a side elevational view of a water jet for producing whirlpool action in bathtubs showing my new design, the opposite side being a mirror image thereof; FIG. 2 is a top plan view thereof;

FIG. 3 is a bottom plan view thereof;

FIG. 4 is a rear elevational view thereof;

FIG. 5 is a front elevational view thereof.

The broken line drawing of suction cups is for illustrative purposes only and forms no part of the claimed design.

FIG. 2

FIG. 5

FIG. 1

FIG. 3

FIG. 4
